UNITED STATES PATENT OFFICE.

JAMES M. McCONNELL, OF GREENSBURG, INDIANA.

FIRE AND BURGLAR ALARM.

1,239,497.

Specification of Letters Patent. Patented Sept. 11, 1917.

Application filed September 23, 1916. Serial No. 121,749.

To all whom it may concern:

Be it known that I, JAMES M. McCONNELL, a citizen of the United States, residing at Greensburg, in the county of Decatur 5 and State of Indiana, have invented new and useful Improvements in Fire and Burglar Alarms, of which the following is a specification.

This invention relates to fire and burglar 10 alarms and it consists in the novel features hereinafter described and claimed.

An object of the invention is to provide 15 an alarm of the character indicated which is automatic in its action and adapted to sound a bell in the event that its active parts are released or disturbed in consequence of the movement of a window sash or door, or in the event that cords employed in the device are severed by the burning action of 20 fire.

With this object in view the device includes a casing having a pulley journaled therein with means for limiting the turning movement of the said pulley. Cables are 25 wound upon the members of the said pulley in opposite directions and are trained through the side of the casing and carry weights at their outer ends. A bell is positioned below one of the said weights, the 30 heavier weight, and is adapted to be sounded by the said weight when the same descends. Another pulley is also journaled in the casing and a lever is attached to the last said pulley. An arm is connected with the said 35 lever and carries a weight. There is a weight adjustably mounted upon the said lever. Cables are attached with the free ends of the lever and arm and may be manually pulled for swinging the lever and arm. 40 Cords pass through the top of the casing and weights are attached to their lower ends the said weights being suspended above the said lever. The last mentioned cords are adapted to be connected with a window sash, 45 doors or beams and when the said cords are permitted to move longitudinally by moving the window sash or the doors or in the event that they are severed by fire, the weights drop upon the lever and actuate the mechanism whereby the bell is sounded.

In the accompanying drawings:—

Figure 1 is a side elevation of the casing with parts removed and showing the arrangement of the mechanism therein.

Fig. 2 is a side elevation of a portion of 55 a sash illustrating the parts which coöperate therewith.

Fig. 3 is a sectional view of the casing cut on the line 3—3 of Fig. 1.

The fire and burglar alarm includes a casing 1 of wood or any other suitable material having a pulley 2, journaled therein. A stop 3 is mounted at the side of the pulley 2 and may engage a cushion 4 mounted at a fixed point within the casing 1 whereby 60 the turning movement of the pulley 2 is limited, the said cushion also preventing noise when the stop engages the same to check the turning movement of the pulley 2. A cable 5 is attached to the periphery of the 65 pulley 2 and is arranged to wind upon the same. The said cable is trained through the end of the casing 1 and carries at its lower end a relatively heavy weight 6. A bell 7 is located below the weight 6 and when the 70 said weight descends and encounters the bell the same is caused to ring and sound an alarm. A cable 8 is attached to the periphery of the pulley 2 and is arranged to wind upon the same in a direction opposite to 75 that in which the cable 5 winds thereon. The cable 8 is also trained through the end of the casing 1 and carries at its outer lower end a relatively light weight 9. Stops 10 and 11 are mounted upon the pulley 2 and 80 project beyond the periphery thereof. A cable 12 is attached to the pulley 2 and is trained through the opposite end of the casing 1 from that end through which the cables 5 and 8 pass. The cable 12 may be pulled 85 manually whereby the pulley 2 is turned to permit the cable 5 to move longitudinally whereby the weight 6 may descend and come in contact with the bell 7 and sound the same. Thus an additional means is provided 90 for operating the alarm. A single pulley 13 is journaled in the casing 1 and is provided with a stop 14 which projects beyond the periphery thereof and into the paths of movement of the stops 10 and 11 hereinbe- 95 100

fore described. A lever 15 is fixed to the pulley 13 and normally lies in an approximately horizontal position. A balancing weight 16 is adjustably mounted upon the lever 15. An arm 17 is connected with the lever 15 and carries at its free end portion a relatively heavy weight 18. The inner end portion of the arm 17 is connected with the lever 15 and consequently they swing in unison. A cable 19 is connected with the free end portion of the lever 15 and is trained through the side of the casing 1 and may be manually pulled for swinging the free end of the lever 15 in a downward direction. A cable 20 is connected with the free end of the arm 17 and is trained through the adjacent side of the casing 1 and may be manually pulled for swinging the free end of the arm in an upward direction.

20. Cords 21 pass through the top of the casing 1 above the free end portion of the lever 15 and weights 22 are attached to the lower inner ends of the cords 21 and hang spaced above the free end portion of the lever 15.

25. The cords 21 are each arranged to wind upon a spool 23 and each spool is designed to be journaled upon a window or door frame.

Assuming that the spool is attached to a window frame and is adapted to be released when the sash is moved in the frame, the spool is provided at its sides with a ratchet wheel or disk 24 and the cord 21 is wound on the said spool so that the attached weight 22 is held in an elevated position above the free end of the lever 15. A pawl 25 is pivoted to the window frame and engages the piece of the ratchet disk 24 whereby the spool 23 is held against turning movement and under the influence of the connected weight 22. A stop 26 is attached to the adjacent window sash 27 and is located below the free end of the pawl 25. The pawl 25 projects into the path of movement of the stop 26 and consequently when the sash 27 is raised the stop 26 comes in contact with the free end of the pawl 25 and lifts the same so that the said pawl disengages the teeth of the ratchet disk 24 and releases the spool 23. Consequently the attached weight 22 falls by gravity and the cord 21 unwinds from the spool 23. When the weight 22 strikes the free end portion of the lever 15 the said lever is swung in a downward direction whereby the pulley 13 is turned so that the stop 14 is carried out of the path of movement of the stop 10 upon the pulley 2. Thus the pulley 2 is released and under the influence of the heavy weight 18 the cable 19 is moved longitudinally and unwinds from the pulley 2 and the said weight comes in contact with the bell and sounds the same. When the pulley 2 turns as just described the cable 19 is wound thereon and the weight

9 is elevated. It is intended that the bell 7 should be placed adjacent the bedside of the person having charge of the property and consequently when the said bell is sounded an alarm is given to indicate that the window sash has been raised. The person who has charge of the apparatus may open the casing 1 and ascertain which of the weights 22 has been lowered and inasmuch as he knows to which window sash the attached cords are trained he is informed as to which window sash has been moved.

When it is desired to reset the mechanism the window sash is lowered and the cord 21 is wound upon the spool 23 and thus the weight 22 is lifted. A pull is exerted on the cable 19 whereby the pulley 13 is turned and the stop 14 is carried out of the path of movement of the stop 10. A pull is exerted upon the cable 8 whereby the said cable is unwound from the pulley 2 and the cable 5 is rewound thereon. When the said pulley 2 is turned the stop 10 is carried back to its normal position. The cable 19 is then released and the stop 14 is moved into the path of the stop 10 by the weight 18 as shown in Fig. 1. The weight 18 acting through the arm 17 will serve to hold the stop 14 in the path of movement of the stop 10 inasmuch as the weight 18 is heavier than the weight 16. The weight 16 is adjustably mounted on the lever 15 in a manner to counterbalance the mechanism to be used with a greater or less number of weights 22.

From the foregoing description taken in conjunction with the accompanying drawing, it will be seen that a fire and burglar alarm of simple and durable structure is provided and that the same is automatic in its action in sounding an alarm after the retaining devices have been moved or ruptured.

Having described the invention what is claimed is:

1. An alarm comprising a casing, a pulley journaled therein, cables arranged to wind upon said pulley in opposite directions and trained through the casing, weights attached to the cables, a bell located below one of the weights, a stop mounted upon the said pulley, a second pulley journaled in the casing, a lever attached to the last mentioned pulley, a stop carried by the last mentioned pulley and located in the path of movement of the first mentioned stop, a weight adjustably mounted upon the lever, an arm connected with the lever, a weight mounted upon the arm and a series of weights held suspended in the casing above the free end portion of the lever.

2. An alarm comprising a casing, a pulley journaled therein, means for cushioning the turning movement of the pulley, a stop carried by the pulley, cables arranged to wind

upon the pulley in opposite directions, weights carried by the cables, a bell located in the path of movement of one of the weights, a second pulley journaled in the casing, a stop mounted upon the last mentioned pulley and located in the path of movement of the first mentioned stop, a

weighted lever attached to the second mentioned pulley, an arm attached to the lever, a weight carried by the arm, and weights 10 held suspended above the free end portion of the said lever.

In testimony whereof I affix my signature.
JAMES M. McCONNELL.
